OUTBOARD PROPELLER MECHANISM FOR
BARGES, SCOWS, AND THE LIKEArthur W. Wanzer, Quincy, Mass., assignor to
Murray & Tregurtha, Inc., Quincy, Mass., a
corporation of Massachusetts

Application February 13, 1943, Serial No. 475,744

10 Claims. (Cl. 115—35)

1

This invention relates to outboard propeller mechanism for barges, scows and similar boats and particularly to mechanism of this type in which the power generator element, the propeller and the driving connections between the power generator and the propeller are built as a unitary structure that can be readily installed on the deck of the barge, scow or other boat.

The type of outboard propeller mechanism herein illustrated is one in which the propeller is mounted for swinging movement about a horizontal axis so that it can be swung out of the water, and in which the propeller and its driving shaft may be turned about a vertical axis and thus used for steering the boat.

One of the objects of the present invention is to provide improvements in both the means employed for turning the propeller about its vertical axis and the means employed for swinging the propeller upwardly about its horizontal axis.

Further objects of the invention are to provide improved means for lubricating and protecting the driving connections between the power generator and the propeller and otherwise to improve devices of this type as will be more fully hereinafter set forth.

In the drawings:

Fig. 1 is a side view showing the rear end of a barge or scow with my improved propeller mechanism mounted thereon.

Fig. 2 is a rear view of Fig. 1.

Fig. 3 is a top plan view.

Fig. 4 is an enlarged vertical sectional view taken on substantially the line 4—4, Fig. 1.

Fig. 5 is a detailed sectional view showing a slightly different construction from that shown in Fig. 4.

Fig. 6 is an enlarged vertical section through the propeller housing illustrating the part of the driving connections for the propeller.

Fig. 7 is an enlarged side view of the rear end of the base and the upper end of the propeller housing.

Fig. 8 is an enlarged section on the line 8—8, Fig. 3.

Fig. 9 is a section on the line 9—9, Fig. 8.

Fig. 10 is a section on the line 10—10, Fig. 8.

Fig. 11 is an enlarged fragmentary view on the line 11—11, Fig. 9.

In the drawings 1 indicates a barge, scow or other boat which is equipped with my improved propeller mechanism. This mechanism includes a power generator indicated at 2 (see Fig. 1) and a propeller which may be a gas engine or a power generator

2

of any other type, a propeller 3 and suitable driving connections between the power generator 2 and the propeller 3.

The power generator, the propeller and driving connections are all mounted on a base or frame 4 which is adapted to be installed on the deck of the barge or scow 1. Mounted on the supporting base 4 is a supporting shaft 5 which is located in outboard relation and from which the propeller is suspended.

This shaft 5 is shown as being carried by bushings 6 which in turn are mounted in the side elements 7 of the supporting frame 4 as shown in Fig. 4.

15 The driving connections between the power generator and the propeller include the engine shaft 6a (see Fig. 7) which carries at its rear end a bevel gear 7a meshing with a bevel gear 8 that is mounted on the supporting shaft 5. 20 This bevel gear 8 has rigid therewith a second bevel gear 9 which meshes with a bevel gear 10 at the upper end of a vertical driving shaft 11, said shaft at its lower end being connected to the propeller shaft 12 through the bevel gearing 13, 14. The vertical shaft 11 is shown as formed in three sections, an upper section 15, an intermediate section 16 and a lower section 17, these sections being connected by universal joints 18.

25 This vertical shaft 11 and the gearing 13, 14 are enclosed in a suitable propeller housing member 19 (see Fig. 6) which is mounted for turning movement about a vertical axis so that the propeller may be used for steering the boat.

30 This propeller housing member 19 is suspended from a supporting housing that is mounted on the supporting shaft 5, said housing comprising the two cylindrical elements 20, 21 which have a slight telescopic arrangement (see Fig. 4).

35 The section 20 is a stationary section, while the section 21 is capable of turning about the supporting shaft 5 as an axis. The end of the housing section 21 is constituted by a segmental gear 47 which is rotatively mounted on one of the bushings 6, and said housing section is widened at the other end as shown at 101, said widened end being secured to a hanger 85 which is rotatively mounted on the other bushing 6. 40 The housing section 21, therefore, is free to turn about the bushings 6.

45 This housing section 21 is provided on its lower widened end with an extension 22 which is rigid therewith and into which the upper end 23 of the propeller housing 19 extends. The propeller

housing is formed with a flange 102 which engages the underside of the housing extension 22, and this flange is formed with a sealing ring 103 to provide a tight or sealed joint between the propeller housing 19 and the housing extension 22. The housing extension 22 is provided with suitable roller bearings 24 in which the upper end 23 of the propeller housing is mounted, such bearings permitting the turning movement of the propeller housing relative to the housing extension 22 about the axis of the shaft 11.

Situated within the two-part supporting housing 26, 21 is a gear housing for the gears 7a, 8, 9, and 10. This gear housing is also made in two parts and comprises the section 25 through which the engine shaft 6a extends and which is stationary, and the second section 26 which is capable of turning on the supporting shaft 5 with the outer housing section 21. This gear housing section 26 is formed with an extension 27 which contains roller bearings 28 for the upper section 15 of the shaft 11.

For turning the propeller housing 19 about the axis of the shaft 11 in order to steer the boat or to reverse its direction, there is provided a worm gear 29 which is fast on the upper end 23 of the housing 19, said worm gear meshing with a worm 30 on a horizontal shaft 31 that is mounted in the housing extension 22. This shaft 31 extends beyond said housing extension and carries at its outer end a sprocket wheel 32 which is connected by a sprocket chain 33 with a sprocket wheel 34 that is coaxial with the supporting shaft 5.

This sprocket wheel 34 has rigid therewith a bevel gear 35 meshing with a bevel gear 36 on the end of a steering shaft 37 which extends longitudinally of the base 4 and is operatively connected to a steering wheel 38 located at the front end of the base. The driving connections between the shaft 37 and the steering wheel are illustrated in Fig. 8. The steering wheel is carried by a shaft 39 which is provided with a sprocket wheel 40 that is connected by a sprocket chain 41 with another sprocket wheel 42 on the front end of the shaft 37. This steering wheel 38 and its shaft 39 are journaled at the upper end of an upstanding housing 43 which rises from the front end of the base 4. The shaft 37 extends into this housing and the end of the shaft is supported in a bearing 63. The sprocket chain 41 and the sprocket wheels 40 and 42 are thus enclosed in this housing. A casing or cover 84 is provided for enclosing the sprocket chain 33 and the sprocket wheels 32, 34.

The above construction provides means whereby a person standing at the wheel 38 can turn the propeller housing 19 about its vertical axis thereby using the propeller to steer the boat or scow. In order to reverse the direction of movement of the boat or scow, all that is necessary is to turn the propeller housing 19 through 180 degrees to bring the propeller into the dotted line position shown in Fig. 1.

I have stated above that the propeller is mounted so that it can be swung upwardly to raise it out of the water.

As stated above, the propeller housing 19 is supported from the housing extension 22 which in turn is rigid with the housing section 21 (see Fig. 4). This housing section 21 is mounted for turning movement about the bushings 6 and hence about the supporting shaft 5 as an axis, and by turning the housing section 21 about its axis, the propeller and propeller housing may be swung

from the full line operative position in Fig. 1 to the elevated inoperative position shown in dotted lines Fig. 1.

The driving connections between the steering wheel 38 and the worm gear 29 are such that they are in no wise affected by any turning movement of the housing section 21 about the horizontal shaft 5, this result being secured by the coaxial relation between the sprocket wheel 34 and the shaft 5. When the propeller housing 19 is swung upwardly about said shaft 5, the shaft 31 and sprocket chain drive 33 swing or move with the propeller housing because of the coaxial relation between the sprocket wheel 34 and the shaft 5. Such swinging movement does not affect in any way the driving connections between the steering wheel and the worm gear 29. In the construction shown in Fig. 4, this sprocket wheel 34 and gear 35 are rigid with a sleeve 45 which is mounted on a reduced extension 46 of the supporting shaft 5.

My present improvements involve novel means for swinging the propeller housing about the supporting shaft 5. The housing section 21 has rigid therewith a segmental gear 47 which is rotatively mounted on one of the bushings 6 and which meshes with a pinion 48 mounted on a shaft 49 that extends transversely of the supporting base 4.

This shaft 49 has at its opposite end a worm gear 50 which meshes with a worm 51 on a shaft 52 extending longitudinally of the base 4 (see Fig. 7). This shaft 52 is connected to a manually operated shaft 53 (see Figs. 9 and 10) that is carried by the housing 43 and which is provided with a crank handle 44 on the exterior of the housing by which it may be turned. The driving connections herein shown between the manually operated shaft 53 and the shaft 52 comprise a sprocket wheel 54 on the shaft 53 connected by a sprocket chain 55 to a larger sprocket 56 on a countershaft 57. This shaft 57 carries a sprocket wheel 58 connected by a sprocket chain 59 with a sprocket wheel 60 on a second countershaft 61, and this shaft 61 is connected to the shaft 52 by a sprocket chain 62 which passes around sprocket wheels 63 and 64 on the shafts 61 and 52 respectively.

The operative connections above described between the crank handle 44 and the gear 47 provide a speed-reducing power increasing driving connection which enables an operator to readily swing the propeller housing and the propeller upwardly about the shaft 5 as an axis notwithstanding the considerable weight of said propeller and housing.

Furthermore, the worm 51 and worm gear 50 by which the shaft 48 is rotated serve as a lock to hold the propeller housing in any adjusted position. I have, however, provided an additional lock for this purpose in the form of a brake drum 89 fast on the shaft 49 and a brake band 90 encircling said drum and which can be clamped thereto by a brake handle 88 (see Fig. 7). This brake handle is pivoted to one end of the brake band 90 as shown at 91, and a link 93 is pivoted at one end to the other end of the brake band as shown at 92 and to the handle as shown at 94. The brake band 90 is shown in Fig. 7 as being set on to the brake drum, but by raising the brake handle 88, the gripping action of the brake band on the brake drum will be loosened thus permitting the shaft 49 to be freely turned.

Another feature of the invention relates to a novel way of maintaining the gearing and bear-

ings of the various shafts of the driving connections properly lubricated.

Situated in the chamber 67 of the propeller housing 19 is an oil pump 68 which is actuated from a gear 69 carried by the propeller shaft (see Fig. 6). The discharge from this pump is connected by a pipe 70 to the lower end of a passage 71 with which the wall of the propeller housing is provided, said passage at its upper end opening into an annular oil-containing chamber 72. This oil chamber 72 is formed in a fitting 73 which is rigid with the casing extension 22 (see Fig. 4) and is shown as connected to the gear housing extension 27 by bolts 95. 96 is a sleeve which is clamped between the housing extension 27 and the fitting 73 by the bolts 95 and through which the shaft section 15 extends. The upper end 23 of the propeller housing is provided with a head 74 having an upstanding annular flange 75 which is partially received in the fitting 73. 76 indicate packing rings that are interposed between the upstanding flange 75 and the walls of the chamber 73 thus making a tight joint. This construction provides a swivel connection between the upper end of the housing 23 and the fitting 73 which allows the housing to turn about the axis of the shaft 11.

The oil chamber 72 has a pipe 77 leading upwardly therefrom, the end of which extends through the gear housing section 26 as shown at 78.

It will be understood that the chamber 67 will be filled with oil or suitable lubricant. The pump 68 takes this oil and forces it through the pipe 70 and passage 71 into the annular oil chamber 72 from which it flows upwardly through the pipe 77 into the interior of the gear housing 25, 26. The oil then flows downwardly through the bearings 28 and through the propeller housing 19 back into the sump 67.

During this circulation of the oil, all the gears and the bearings are properly lubricated. The swivel connection between the upper end of the housing section and the fitting 73 permits the housing section to be turned about the axis of the shaft 11 without in any way interfering with the circulation of the oil.

In Fig. 5, I have shown a slightly different embodiment of the invention wherein the sprocket wheel 34 and bevel gear 35a are mounted on a shaft separate from the supporting shaft 5 but in axial alignment therewith. In this embodiment, the sprocket wheel 34 is fast on a short shaft 79 supported in suitable bearings 80, said shaft being situated coaxially with the supporting shaft 5.

This shaft 79 has rigid therewith a bevel gear 35a which meshes with a bevel gear 36a on the end of the shaft 37. The coaxial alignment of the shafts 79 and 5 permit the propeller housing to be swung upwardly about said shaft 5 without interfering in any way with the operation of the steering mechanism.

There is also provided herein an indicator which is situated adjacent the steering wheel and which indicates the extent to which the propeller housing has been turned about its vertical axis thus assisting the operator in steering the boat, such indicator being illustrated in Figs. 8, 9, and 11.

The shaft 39 of the steering wheel has rigid therewith a spiral gear 31 which meshes with a companion gear 82 on the lower end of a vertical shaft 83. This shaft 83 carries at its upper end some suitable pointer or indicator arrangement

which the party operating the steering wheel 38 can easily observe.

Any turning of the steering wheel in either direction will thus operate to shift the position of the pointer and by employing a properly graduated dial, the operator can observe from the indicator just what the angular position of the propeller housing is at any time.

86 indicates guard wings which are attached to the propeller housing and which serve to guard or protect the propeller (see Fig. 1).

In the construction shown, the gear housing 25, 26 is carried by the two bushings 6. The stationary section 25 of the gear housing has a sleeve-like hub 98 in which is received the inner end of one of the bushings 6, and the other gear housing section 26 has the sleeve-like hub 99 in which is received a second sleeve 100 carried by the other bushing 6.

20 The housing members 25, 26 are provided with roller bearings 97 (see Fig. 4) for the double gear 8, 9, said gear, therefore, being directly supported by the gear housing which in turn is supported on the supporting shaft 5.

25 By mounting the base 4 on the boat so that the rear end is raised slightly, the resulting position of the propeller will tend to depress the stern of the boat slightly and to raise the bow thereof, thereby enabling the speed of the boat to be increased.

30 I claim:

1. An outboard propeller mechanism for boats comprising a base adapted to be mounted on the deck of a boat, a supporting shaft carried by said base in outboard relation, a housing member mounted on said shaft to turn thereabout, a propeller housing carried by said housing member, a propeller carried by said propeller housing, means to operate the propeller, a gear rigid with said housing member, a shaft extending transversely of the base, a pinion on said shaft meshing with said gear, a shaft extending longitudinally of the base, a worm and worm gear connection between said transversely extending shaft and longitudinally extending shaft, means at the front end of the base to rotate said longitudinally extending shaft and thus swing the propeller housing and propeller upwardly about the supporting shaft, and a manually operated brake for locking the transversely extending shaft from rotation.

2. An outboard propeller mechanism for boats comprising a base adapted to be mounted on the deck of a boat, a supporting shaft carried by said base in outboard relation, a housing member mounted on said shaft to turn thereabout, a propeller housing carried by said housing member, a propeller carried by said propeller housing, means to operate the propeller, a gear rigid with said housing member, a shaft extending transversely of the base, a pinion on said shaft meshing with said gear, a shaft extending longitudinally of the base, a worm and worm gear connection between said transversely extending

55 shaft and longitudinally extending shaft, means at the front end of the base to rotate said longitudinally extending shaft and thus swing the propeller housing and propeller upwardly about the supporting shaft, and a manually operated brake for locking the transversely extending shaft from rotation, said brake comprising a brake drum on said transversely extending shaft and a manually controlled brake band encircling said drum.

3. An outboard propeller mechanism for boats comprising a base adapted to be mounted on the deck of a boat, a supporting shaft carried by said

base in outboard relation, a housing member mounted on said shaft to turn thereabout, a propeller housing carried by said housing member, a propeller carried by said propeller housing, means to operate the propeller, means operative from the front end of the base to turn the housing member about the supporting shaft and thus swing the propeller upwardly, said propeller housing being turnable about an axis at right angles to the supporting shaft for steering the boat, a steering wheel carried by said base at the front end thereof and connections between said steering wheel and said propeller housing by which turning movement of the steering wheel turns the housing about its axis, said connections being operative in any position which the propeller housing assumes as it turns about the supporting shaft.

4. An outboard propeller mechanism for boats comprising a base adapted to be mounted on the deck of a boat, a supporting shaft carried by said base in outboard relation, a housing member mounted on said shaft to turn thereabout, a propeller housing carried by said housing member, a propeller carried by said propeller housing, means to operate the propeller, means operative from the front end of the base to turn the housing member about the supporting shaft and thus swing the propeller upwardly, said propeller housing being turnable about an axis at right angles to the supporting shaft for steering the boat, a steering wheel carried by said base at the front end thereof and connections between said steering wheel and said propeller housing by which turning movement of the steering wheel turns the housing about its axis, said connections including a gear coaxial with the supporting shaft, whereby said connections are operative in all positions which the propeller housing assumes as it swings about the supporting shaft.

5. An outboard propeller mechanism for boats comprising a supporting base adapted to be mounted on the deck of a boat, a horizontal supporting shaft carried by said base in outboard relation, a propeller housing, a propeller carried by said housing, means supporting the propeller housing from said shaft to permit it to swing bodily about said shaft to raise the propeller and when in vertical position to turn about a vertical axis for steering the boat, means to operate the propeller, a steering shaft extending longitudinally of the base, a countershaft extending transversely of the base and having a worm and gear connection with the propeller housing, driving connections between said steering shaft and said countershaft including a gear coaxial with the supporting shaft, a steering wheel at the front end of the base and driving connections between said steering wheel and said steering shaft.

6. An outboard propeller mechanism for boats comprising a base adapted to be mounted on the deck of the boat, a supporting shaft carried by said base in outboard relation, a gear housing mounted on said supporting shaft, a propeller housing, means for suspending the propeller housing from said shaft, a propeller carried by the propeller housing, means for driving the propeller including a driving shaft extending axially of the propeller housing and transmission gearing on said supporting shaft enclosed in the gear housing, said propeller housing being turnable about a vertical axis for steering the boat and having an oil sump in its lower end and an oil passage in its wall which communicates at its lower end with said sump, means providing an

annular oil chamber at the upper end of the propeller housing with which the oil passage communicates, a pipe connection between said annular oil chamber and the gear housing, and means for circulating oil from the sump through said oil passage and annular oil chamber into the gear housing.

7. An outboard propeller mechanism for boats comprising a base adapted to be mounted on the deck of the boat, a supporting shaft carried by said base in outboard relation, a housing member mounted on said shaft, a propeller housing carried by said housing member and adapted for turning movement about an axis perpendicular to that of the supporting shaft, a propeller carried by said propeller housing, means for driving the propeller including a driving shaft extending axially of the propeller housing and transmission gearing mounted on said supporting shaft, a gear housing carried by said shaft enclosing said transmission gearing, said propeller housing having an oil sump in its lower end and an oil passage in its wall which communicates with said sump, means providing an annular oil chamber at the upper end of the propeller housing with which said oil passage communicates, a pipe connection between said annular oil chamber and the gear housing, and means for circulating oil from the sump through said oil passage and annular oil chamber into the gear housing.

8. An outboard propeller mechanism for boats comprising a base adapted to be mounted on the deck of a boat, a two-part supporting housing carried by said base in outboard relation, one part of said housing being stationarily mounted on the base and the other part being mounted to turn about a horizontal axis, a propeller housing depending from the turnable part of the supporting housing, a propeller carried by said propeller housing, a gear housing located within the supporting housing, means to operate the propeller including transmission gears within said gear housing, and means operative from the front end of the base to turn the turnable portion of the supporting housing about its horizontal axis and thus swing the propeller housing and propeller upwardly.

9. An outboard propeller mechanism for boats comprising a base adapted to be mounted on the deck of the boat, a two-part supporting housing carried by said base in outboard relation, one part of said housing being stationarily mounted on the base and the other part being mounted to turn about a horizontal axis, a propeller housing depending from the turnable part of the supporting housing, a propeller carried by said propeller housing, a gear housing located within the supporting housing, means to operate the propeller including transmission gears within said gear housing, the latter having bearings in which the transmission gears are rotatively supported, and means operative from the front end of the base to turn the turnable portion of the supporting housing about its horizontal axis and thus swing the propeller housing and propeller upwardly.

10. An outboard propeller mechanism for boats comprising a base adapted to be mounted on the deck of the boat, a two-part supporting housing carried by said base in outboard relation, one part of said housing being stationarily mounted on the base and the other part being mounted to turn about a horizontal axis, a propeller housing depending from the turnable part of the sup-

porting housing, a propeller carried by said propeller housing, a gear housing located within the supporting housing and also comprising two parts, one of which is stationary and the other of which is turnable about said horizontal axis with the turnable part of the supporting housing, and means operative from the front end of the base to turn the turnable portion of the two housings about said horizontal axis and thus swing the propeller housing and propeller upwardly.

ARTHUR W. WANZER.
